ABSTRACT

A valveless-type down-the-hole hammer drill which has an inner tube extending from the upper end of the hammer body into a central opening in a cutter bit reciprocably mounted in a chuck on the opposite end of the hammer body. High pressure fluid is supplied to the interior of the inner tube and a piston surrounding the inner tube has internal surfaces controlling connection of a port to chambers above and below the piston. The external surface of the piston controls connection of these chambers to an exhaust port. A valve sleeve on the chuck coacts with the piston in this respect.

FIG. I.

FIG. 2.

HAMMER DRILLS FOR MAKING BOREHOLES

This is a division of application Ser. No. 07/178,688, filed Apr. 6, 1988, now U.S. Pat. No. 4,921,056.

This invention relates to hammer drills for making boreholes.

It is already known to employ hammer drills of the so-called "down-the-hole" type for drilling boreholes. Such hammer drills employ a hammer mechanism built into a drill head and driven by a pressurised fluid supply to apply repeated percussive blows to a drill bit carried by the drill head.

There are two basic types of hammer mechanisms, namely valveless mechanisms and valved mechanisms. In the latter type, a pressure operated valve directs the flow of pressurised fluid to act on one end of a hammer piston or the other. In the valveless type, the hammer piston itself acts as a valve, such that various fluid flow passages are opened or closed in accordance with the position of the piston. The present invention is concerned with hammer drills of the valveless type.

Many different designs of valveless hammer mechanisms are already known, but the existing designs make use of very complex piston designs in which there are 25 complicated port and/or passage configurations formed in the hammer piston itself. Since the hammer piston is subjected in use to very high loads, these complex configurations can result in damage to the piston.

It is an object of the invention to provide a valveless 30 type hammer drill in which this disadvantage is avoided.

In accordance with the invention there is provided a valveless-type hammer drill comprising a body tube adapted at one end for attachment to a tubular drill string, a chuck mounted on the opposite end of said body tube, a cutter bit retained by said chuck and movable axially relative thereto, an inner tube extending coaxially within the body tube and slidably engaged in a bore in the cutter bit, an annular section piston slidably mounted on the inner tube, the piston coacting with ports formed in the wall of the inner tube in controlling the supply of high pressure fluid from said inner tube to chambers between the inner tube and the body tube and disposed respectively at opposite ends of the 40 body tube, an exhaust port formed in the chuck and valve surfaces on the exterior of the piston coacting with the wall of the body tube and with a valve sleeve on the chuck in controlling communication of said chambers with said exhaust port, whereby, in use, the piston is reciprocated in the body and repeatedly delivers percussive blows to the cutter bit.

The provision of an inner tube extending completely through the piston and providing the high pressure porting for the hammer mechanism enables the piston 55 shape to be kept very simple indeed. The interior of the piston may be of simple stepped cylindrical shape. Similarly the exterior shape can also be kept extremely simple.

Not only does this simplicity of piston shape avoid 60 the stress concentrations which ultimately gave rise to the piston damage in the known complex shape pistons, but it also enables the maximum piston cross-sectional area to be employed in a body tube of given size. This feature is of particular importance when the invention is 65 applied to a sampling hammer drill, having a sample tube inside the inner tube. This invention is, however, also applicable to hammer drills without any sample

tube, in which the exhausted fluid escapes up through the borehole.

In conventional hammer drills communication between an exhaust port and a chamber in the body at the 5 cutter bit side of the piston is controlled by a valving element mounted on the cutter bit (or an anvil which transmits percussive blows to the cutter bit). The valving element is usually a tube the interior of which is effectively an exhaust port through which hammer exhausts exits into the borehole via passageways in the cutter bit.

This conventional arrangement has many disadvantages. Firstly, the centrally positioned tubular valve element is likely to be damaged as a result of any slight misalignment between the piston and the bit which may develop when the bit starts to wear. Such damage will rapidly reduce the efficiency of the hammer. The valve element is frequently formed of nylon, which has a tendency to absorb oil and swell so that it seizes or becomes detached. Furthermore, the known construction cannot be applied to sampling-type hammer drills in which a central tube is used to return chippings etc. cut by the hammer to the ground surface via a second tube within the drill string.

It is thus another object of the present invention to provide a valveless-type hammer drill in which these and other disadvantages are avoided.

Accordingly the invention also provides a valveless-type hammer drill comprising a body tube adapted at one end for attachment to a drill string via which a supply of high pressure fluid is connected in use to the hammer drill, a chuck mounted on the opposite end of said body, a cutter bit retained by said chuck for axial movement relative thereto, a piston within said body reciprocable axially therein into percussive contact with the cutter bit, supply control means co-operating with the piston and selectively connecting chambers within the body tube at opposite sides of said piston to said supply according to the axial position of the piston, and exhaust control means co-operating with said piston and selectively connecting said chambers to an exhaust port in accordance with the axial position of the piston, said exhaust control means including a sleeve on the chuck projecting towards said one end of the body tube, an annular space surrounding said sleeve communicating with said exhaust port and the sleeve being arranged to receive one axial end of the piston and cut the associated chamber off from the exhaust port when the piston is approaching the cutter bit.

The invention also resides in a valveless-type hammer drill in which a hammer piston reciprocable by fluid pressure is percussively contactable with a cutter bit, said piston coacting with a foot valve element whereby communication between an exhaust port and a chamber on one side of said piston is interrupted as the piston approaches the cutter bit, characterised by the fact that said foot valve element comprises a sleeve formed on a chuck which retains said cutter bit, the interior of the sleeve receiving the end of the piston as it approaches the cutter bit.

IN THE ACCOMPANYING DRAWINGS

FIG. 1 is a longitudinal sectional view showing one example of the invention; and

FIG. 2 is a similar view showing another example.

Referring firstly to FIG. 1, the hammer drill shown is of the sampling type, that is to say it incorporates a sample tube 10 through which chippings etc. cut by the

drill are returned to the surface in use entrained with at least a portion of the pressurised fluid (for example compressed air) which is supplied to the drill via the outer annular section passageway of a coaxial dual tube drill string.

The drill includes a body tube 11 which is adapted at its upper end to be fitted to the end of the outer tube of the drill string. To this end, the body tube 11 has a screw thread 11a.

Mounted on the lower end of the body tube is a chuck 12 which retains a cutter bit 13. The chuck 12 is screw-threadedly engaged with the body tube and has at its lower end three axially projecting dogs 12a which fit into corresponding recesses in the exterior of the cutter bit 13 so as to provide a driving connection between the body tube and the cutter bit 13. The cutter bit 13 is retained in the chuck by means of three plugs 14 which are fitted in bores in the wall of the chuck and project into three longitudinally extending grooves 13a in the exterior of the shank of the cutter bit. These plugs permit axial movement of the cutter bit between the two positions shown in the right and left hand halves of FIG. 1. The plugs 14 are retained by containment within the lower end of the body tube.

Surrounding the sample tube 10 is an inner tube 15 which extends from substantially the upper end of the body tube coaxially therewith into sliding engagement with an axial bore in the shank of the cutter bit 13. As will be seen from FIG. 1 the inner tube is sufficiently long to remain in engagement with this bore even when the cutter bit is in its lowered position as shown in the left hand half of FIG. 1. An "O" ring seal 16 is shown fitted in the bore in the cutter bit shank, but this may not always be necessary.

The upper end of the inner tube 15 is externally of stepped configuration which fits in a stepped bore in a mounting disc 17 mounted at the upper end of the body tube. A pair of spring washers 18 are compressed between the end of the inner tube 15 and a non return valve body 19 fitted in the body tube. Wavy spring washers 20 are compressed between this valve body and an annular non-return valve closure element 21 which seat on an annular valve seat 22. This seat is fastened to the sample tube and the whole assembly is held together by the coupling thereto of the dual tube drill string (not shown). The non-return valve ensures that reverse flow up the drill string cannot occur at times when the compressed air supply is turned off. This prevents ground water carrying mud particles entering the working parts of the hammer mechanism and causing damage thereto.

In the annular section space between the inner tube and the body tube an annular section hammer piston 25 is reciprocably mounted. This piston is slideable on the inner tube 15 and also slidably engages the interior of the body tube. The piston divides the annular section space referred to into upper and lower chambers 26 and 27. The piston itself controls airflow to and from these chambers.

In the left hand half of FIG. 1 which shows the piston in a raised position the annular passage 28 between the inner tube 15 and the sample tube 10 communicates with the upper chamber 26 via ports 15a in the inner tube. In this position a land 15b on the inner tube 15 above the ports 15a lies within an inner region of the piston 25 which is of greater internal diameter than upper and lower end regions of the piston 25, so that there is an annular clearance between the inner tube 15

and the piston 25 providing the connection between the ports 15a and the upper chamber 26. The piston itself is a close fit in this position in an upper reduced internal diameter zone 11b of the body tube 11, so that there is no communication between the upper and lower chambers externally of the piston. A land 15c on the inner tube 15 below the ports 15a engages the lower end region of the piston 25 to isolate the upper and lower chambers from one another internally of the piston. In normal use, the cutter bit 13 is in the raised position shown on the right hand side of FIG. 1 and, in this position and with the piston raised, the lower chamber is opened to exhaust via exhaust ports 12b in the chuck wall.

In the lowered position of the piston 25 shown in the right hand half of FIG. 1, it is the lower land 15c on the tube 15 which lies within the inner region of the piston and the upper land 15b engages the upper end region of the piston. The lower end of the piston engages in a valve sleeve portion 12c which extends upwardly from the upper end of the chuck 12. A fluted portion 15d on the inner tube below the lower land 15c engages in the lower end region of the piston to provide an adequate central location for the tube 15 in this position. There is thus provided a high pressure fluid flow connection between the ports 15a and the interior of the valve sleeve portion 12c. A connection between the upper chamber 26 and the exhaust ports 12b is provided via flutes or flats 25a formed on the exterior of the piston at its upper end. Starting from the position shown in the right hand half of FIG. 1, a cycle of operation of the hammer is as follows:

(a) The high pressure acting on the lower end of the piston accelerates the piston upwardly.

(b) The first change in the connections described above occurs when the land 15c engages the lower end region of the piston. This blocks the connection between the high pressure ports 15a and the lower chamber, but high pressure fluid trapped in this chamber continues to urge the piston upwardly and it therefore continues to accelerate upwardly.

(c) This situation continues until the communication between the upper chamber 26 and the ports 12b is blocked when the unslotted part of the piston enters the reduced part 11b of the body. By now, the piston has achieved a considerable upward velocity and this closing off of the upper chamber causes the fluid trapped therein to be compressed thereby initiating slowing of the piston.

(d) Very shortly after step (c) the lower end of the piston 25 leaves the valve sleeve portion 12c and the land 15b enters the inner region of piston 25. The lower end of the piston is now at exhaust pressure and high pressure is applied to the upper end causing rapid slowing of the piston until it comes to rest in the position shown in the left hand half of FIG. 1. The piston then starts to accelerate downwardly.

(e) The reverse sequence now occurs, with the piston motion being cushioned when the piston reaches the sleeve portion 12c. The piston eventually strikes the upper end of the cutter bit shank and then the whole cycle recommences.

For flushing away of chippings cut by the cutter bit as a result of repeated percussive blows being delivered thereto whilst it is being rotated (by rotation of the drill string by a surface level rig) a small proportion of the air supplied to the drill is allowed to pass beyond the ports 15a into an annular passage 30 formed between the

lower end of the sample tube 10 and the interior of the cutter bit stem. Fitted into the interior of the cutter bit stem is an air flow reversing device 31 which includes a tubular portion 31a extending upwardly into the interior of the sample tube which is internally enlarged to receive this tubular portion. The sample tube 10 and the tubular portion 31a together define an annular nozzle the axial length of which is very much larger than the width of the annular gap (i.e. the difference between the internal and external radii of the annular nozzle). This 10 ensures a strong upward flow of high pressure air into the sample tube which can entrain the chippings or other material and carry it away up the sample tube.

It is to be noted that the annular nozzle construction described in the immediately preceding paragraph may 15 be regarded as a feature of the hammer drill which is independent of the specific hammer construction, that is the nozzle construction could be used with other types of hammer drill.

Turning now to FIG. 2 it will immediately be appreciated by the reader skilled in this art that no sample tube is included. In principle, however, the design of the hammer mechanism is the same as that shown in FIG. 1, except that the inner tube is of smaller diameter. Parts shown in FIG. 2 which correspond to parts included in 25 FIG. 1, have the same reference numerals increased by 100 and will not be redescribed.

It will be noted that the lower end of the inner tube 115 terminates in a flow restrictor plug 140 through which additional flushing air can flow into a passage in 30 the bit 113. This passage opens on to the lower face of the bit 113 and provides a supply of air in addition to the hammer exhaust to cool the bit face and blow away chippings etc. The plug 140 may have a variable orifice or it may be selected from a range of different plugs to 35 suit the cutting bit in use and the working conditions.

I claim:

1. A valveless down-the-hole hammer drill for use with a drill string supplying high pressure fluid to the hammer drill, comprising:
  - a body tube having an upper end for attachment to a drill string;
  - a chuck secured to said body tube at a lower end thereof;
  - a cutter bit carried by said chuck;
  - cooperating means on said chuck and said cutter bit mounting said cutter bit for limited axial movement relative to said chuck;
  - a piston within said body tube reciprocable axially therein into percussive contact with said cutter bit and defining with said body tube upper and lower chambers at opposite ends of said piston;
  - supply control means cooperable with said piston and responsive to axial movement thereof for selectively connecting said upper and lower chambers and the pressure fluid supply from the drill string according to the axial position of said piston in said body tube;
  - an exhaust port;
  - exhaust control means cooperable with said piston and responsive to axial movement thereof for selectively connecting said upper and lower chambers to said exhaust port according to the axial position of the piston in said body tube;
  - said exhaust control means including a foot valve sleeve mounted on said chuck surrounded by an annular space in communication with said exhaust port;

said piston being reciprocable between a raised position in which pressure fluid is supplied to the upper chamber, the lower end of the piston is clear of the foot valve sleeve, and said lower chamber is connected to said exhaust port through said annular space whereby the piston is urged downwardly and a lower position in which pressure fluid is supplied to the lower chamber, the lower end of the piston is sealingly engaged in the foot valve sleeve to seal the lower chamber from the exhaust port, and the upper chamber is connected to the exhaust port whereby the piston is urged upwardly.

2. A hammer drill according to claim 1 wherein said foot valve sleeve extends axially upwardly from said chuck into said lower chamber, said supply control means including means for supplying pressure fluid into said sleeve when said piston lies in said lower position thereof in sealing engagement with the foot valve sleeve.

3. A hammer drill according to claim 1 wherein said cutter bit includes means defining a central passageway, an inner tube carried by the drill string, a sample tube within said inner tube and defining with said inner tube an annular space therebetween in communication with the pressure fluid supply from the drill string, means defining with said sample tube an annular nozzle disposed within said central passageway and arranged to direct fluid flowing through said annular space between said inner tube and said sample tube upwardly into the lower end of said sample tube.

4. A hammer drill according to claim 3 wherein said nozzle is formed by a fluid flow reversing device carried by said cutting bit and including a tubular portion extending into the lower end of said sample tube.

5. A hammer drill according to claim 4 in which said tubular portion extends into the lower end of said sample tube a distance greater than the width of the annular space formed between the tubular portion and the sample tube.

6. A valveless down-the-hole hammer drill for use with a dual-wall drill string, comprising:

- a body tube for attachment at one end to the drill string;
- a lining tube mounted co-axially in the body tube, said lining tube having supply ports therein;
- an annular hammer piston mounted between the body tube and the lining tube for axial reciprocation relative thereto and in part defining upper and lower chambers;
- a cutter bit;
- means mounted said cutter bit on the opposite end of the body tube for limited axial displacement relative thereto;
- means including said lining tube defining a high pressure fluid supply passage for conveying pressure fluid for driving the hammer piston from the drill string to said supply ports in the lining tube and alternatively to said upper and lower chambers in response to axial reciprocation of said piston;
- an annular foot valve sleeve fixedly mounted in the body tube adjacent said opposite end thereof;
- means defining an exhaust port adjacent said opposite end of the body tube and alternately in communication with said upper and lower chambers in response to axial reciprocation of said piston;
- said hammer piston being reciprocable between a raised position in which pressure fluid is applied to said upper chamber via said supply ports, said pis-

ton is axially spaced from said foot valve sleeve, and communication between the supply ports and the exhaust port is blocked by engagement between the piston and said lining tube, and a lowered position in which fluid pressure is applied to said lower chamber via said supply ports and the lower end of the piston is in engagement with said foot valve sleeve to block communication between said supply ports and said exhaust port;

whereby said piston is caused to reciprocate and 10 deliver repeated blows to the cutter bit.

7. A hammer drill according to claim 6 wherein said cutter bit has a axial passageway, a sample tube within said lining tube and defining with said lining tube an annular space therebetween, means defining with said lining tube an annular nozzle disposed within said axial passageway and arranged to direct pressure fluid flowing through said annular space between said sample tube and said lining tube upwardly into the lower end of said sample tube.

8. A hammer drill according to claim 7 wherein said nozzle is formed by a fluid flow reversing device carried by said cutting bit and including a tubular portion extending into the lower end of said sample tube.

9. A hammer drill according to claim 8 in which said tubular portion extends into the lower end of said sample tube a distance greater than the width of the annular space formed between the tubular portion and the sample tube.

10. A waveless down-the-hole hammer drill for use 30 with a dual-wall drill string, comprising:

a body tube for attachment at one end to the drill string,

a lining tube mounted co-axially in the body tube, said lining tube having supply ports therein;

a sample tube mounted in the lining tube;

an annular hammer piston carried by the drill between the body tube and the lining tube for axial reciprocation relative thereto and, in part, defining upper and lower chambers in alternate communication with said supply ports in response to axial reciprocation of said piston;

a cutter bit;

means mounting said cutter bit adjacent the opposite end of said body tube for limited axial displacement 45 relative thereto;

said lining tube and said sample tube being shaped and dimensioned to define between them a high pressure fluid supply passage for conveying pressure fluid for driving the hammer piston from the 50 drill string to said supply ports in the lining tube and alternately to said upper and lower chambers; an annular foot valve sleeve fixedly mounted in said body tube adjacent said opposite end thereof; an exhaust port located at said opposite end of the 55 body tube;

said hammer piston being reciprocable between a raised position in which pressure fluid is applied to said upper chamber via said supply ports, said piston is axially spaced from said foot valve sleeve, 60 and communication between the supply ports and

the exhaust port is blocked by engagement between the piston and said lining tube, and a lowered position in which fluid pressure is applied to said lower chamber via said supply ports and the lower end of the piston is in engagement with said foot valve sleeve to block communication between said supply ports and said exhaust port;

whereby said piston is caused to reciprocate and deliver repeated blows to the cutter bit;

an annular flushing nozzle located within said passageway of the cutter bit for directing flushing fluid upwardly into the sample tube;

said lining tube and said sample tube being further shaped and dimensioned to provide passageway connecting said pressure fluid supply passage to the flushing nozzle for supplying pressure fluid to said flushing nozzle.

11. A valveless down-the-hole hammer drill for use with a drill string supplying high pressure fluid to the hammer drill, comprising:

a body tube having an upper end for attachment to a drill string;

a chuck secured to said body tube at a lower end thereof;

a cutter bit carried by said chuck;

cooperating means on said chuck and said cutter bit mounting said cutter bit for limited axial movement relative to said chuck;

a piston within said body tube reciprocable axially therein into percussive contact with said cutter bit and defining with said body tube upper and lower chambers at opposite ends of said piston;

supply control means cooperable with said piston and responsive to axial movement thereof for selectively connecting said upper and lower chambers and the pressure fluid supply from the drill string according to the axial position of said piston in said body tube;

an exhaust port;

exhaust control means cooperable with said piston and responsive to axial movement thereof for selectively connecting said upper and lower chambers to said exhaust port according to the axial position of the piston in said body tube;

said exhaust control means including a foot valve sleeve fixedly mounted in said body tube adjacent the lower end thereof;

said piston being reciprocable between a raised position in which pressure fluid is supplied to the upper chamber, the lower end of the piston is clear of the foot valve sleeve, and said lower chamber is connected to said exhaust port whereby the piston is urged downwardly and a lower position in which pressure fluid is supplied to the lower chamber, the lower end of the piston is sealingly engaged in the foot valve sleeve to seal the lower chamber from the exhaust port, and the upper chamber is connected to the exhaust port whereby the piston is urged upwardly.
